UNITED STATES PATENT OFFICE.

THOMAS JOHN ATKINSON, OF GRAND RAPIDS, MICHIGAN.

DESIGN FOR A CLOTHES-PIN MEMBER.

SPECIFICATION forming part of Design No. 29,799, dated December 13, 1898.

Application filed September 19, 1898. Serial No. 691,392. Term of patent 7 years.

To all whom it may concern:

Be it known that I, THOMAS JOHN ATKINSON, a citizen of the United States, residing at Grand Rapids, in the county of Kent and 5 State of Michigan, have invented and produced a new and original Design for a Member of a Clothes-Pin, of which the following is a specification, reference being had to the accompanying drawings, forming a part thereof.

Figure 1 is an illustration of the clothes-pin member in perspective. Fig. 2 is a view of the contour of the aforesaid member. Fig. 3 is a plan view of the outer surface of the aforesaid member. Fig. 4 is a plan view of 15 the inner surface of the member aforesaid.

As shown in the drawings, the leading or material feature of my design consists in the

contour of the clothes-pin member having an outer flat surface A, slightly raised at one end B and traversed by a recess B². The reverse side of the member presents a series of modulated indentations 1, 2, and 3, as shown in Fig. 2, Figs. 3 and 4 being plan views of the perspective and edge views, as shown in Figs. 1 and 2, respectively.

Having thus described my invention, what I claim as new, and desire to secure by Letters Patent, is—

The design for a clothes-pin member, substantially as shown and described.

THOMAS JOHN ATKINSON.
